No. 695,396.

Patented Mar. 11, 1902.

C. H. JOHNSON.

PNEUMATIC HAMMER.

(Application filed June 10, 1901.)

(No Model.)

UNITED STATES PATENT OFFICE.

CHARLES HARRIS JOHNSON, OF CHICAGO HEIGHTS, ILLINOIS.

PNEUMATIC HAMMER.

SPECIFICATION forming part of Letters Patent No. 695,396, dated March 11, 1902.

Application filed June 10, 1901. Serial No. 63,957. (No model.)

To all whom it may concern:

Be it known that I, CHARLES HARRIS JOHNSON, a citizen of the United States, residing at Chicago Heights, in the county of Cook, State 5 of Illinois, have invented certain new and useful Improvements in Pneumatic Hammers; and I hereby declare the following to be a full, clear, and exact description thereof, reference being had to the accompanying drawing, in 10 which is shown a longitudinal central section of a construction embodying my invention.

My invention relates generally to that class of motive-fluid-operated tools commonly termed "pneumatic" hammers or riveters, 15 and especially to the class of hand-tools wherein are combined a cylinder and a differential piston, with suitable ports and means for maintaining a constant motive-fluid pressure on that head of the piston having the 20 lesser area.

The main objects of my invention are, first, to simplify the construction of this class of pneumatic tools, and, second, to uniformly increase the piston mass toward its hammer 25 end or that head having the greater area, so as to add to the efficiency of the blow, while reducing the piston mass to be suddenly arrested by the metal at the front end of the piston.

To this end the invention may be generally stated as residing in the combination of a suitable cylinder and a differential piston, the cylinder having an exhaust-port in that end thereof corresponding to the piston-head having the greater area and the piston having a through-passage or supply-port for that end of the cylinder which contains the exhaust-port, said supply-passage of the piston being constantly open to the pressure-supply, and 35 means for maintaining a constant motive-fluid pressure upon that head of the piston having the lesser area.

I will now proceed to describe my invention more fully by reference to the drawing, so 40 that others skilled in the art to which it appertains may apply the same.

In the drawing, A indicates a suitable cylinder, some of the internal diameters of which will correspond with the piston to be used 45 therewith, while others may exceed the same for purposes which will hereinafter appear.

The lower end of said cylinder A will be provided with a ferrule A' for the reception of a "snap" or die a, commonly used with this class of tools, and said ferrule and snap will 55 when in place constitute one head of the cylinder, the opposite head of the cylinder being constituted by the screw plug or cap C, which latter also serves to unite the handle D with the cylinder A. The ferrule A' may be provided with a flange or collar a' and introduced through the front end of the cylinder.

The handle D may be of any suitable form and is provided with a motive-fluid-supply passage d, which communicates with that end 65 of the cylinder containing the lesser head of the differential piston, and said supply-passage d is provided with the usual or any approved throttle-valve E, which may be operated by a suitable lever e, pivoted on the handle D.

The central portion of the cylinder A is of an internal diameter corresponding to the diameter of that head of the piston having the greater area, as at 1 1, and is increased at one 75 end, (or at the lower end of the cylinder,) as at 2 2, to afford a clearance for the piston and at the other end, (or above,) as at 3 3, to receive an inserted sleeve 4, which reduces the inner diameter of the cylinder to correspond 80 with that head of the piston having the lesser area.

The inserted sleeve 4 for reducing the internal diameter of the cylinder permits the ferrule A' and the piston 7 to be inserted from 85 the upper or handle end of the cylinder, thus simplifying the construction and reducing the number of joints of the device.

5 indicates an exhaust-port, and 6 a relief-port for preventing any pressure from leakage on the reverse stroke of the piston.

7 indicates a differential piston of tubular form or having a hollow center 7^a, (see dotted lines,) which is open toward the motive-fluid supply d of the cylinder and closed at the opposite or hammer end except for one or more radially-arranged ports or passages 7^b, (see dotted lines,) which serve as supply-ports for the opposite or lower end of the cylinder and which are closed (or cut off) by the cylinder-walls on the reverse stroke of the piston before the exhaust-port e is opened.

The construction being substantially such as hereinbefore pointed out, the device will operate as follows: The piston being in the position shown in the drawing and constant motive-fluid pressure being maintained through supply-port d on the lesser head of the piston, the motive fluid will pass through the hollow core 7^a of the piston and by the supply-ports 7^b therethrough to the opposite end of the cylinder or the greater head of the piston, which will impart to the piston its lift or return movement. The piston continues its lift or return movement under direct pressure until the ends of the supply-ports 7^b are closed by the walls of the cylinder and then by expansion until the lower end of the piston passes and opens the exhaust-ports of cylinder A, when exhaust occurs, the motion of the piston is reversed, and its hammer blow is delivered. Just before the hammer blow is struck the supply-ports 7^b are opened, and the lift or return movement of the piston will commence as soon as its blow has been delivered.

25 The arrangement of the supply-ports which pass through the piston and the exhaust port or ports of the cylinder is such that the piston-ports 7^b never act as exhaust-ports, and the relative arrangement of said ports will determine the length and rapidity of the piston movement.

It will be noted that a characteristic feature of the present construction is the admission-port which passes through the piston and the formation at the lower end of the piston which cuts off the supply of air to the under side, and the particular value of such a construction resides in the fact that it is not necessary to close the back end of the piston, and in consequence the weight of the piston can be uniformly increased from the back end downward, (or to the hammer end,) thus causing

the least possible mass to be suddenly stopped by the metal at the front of the piston.

Having thus described my invention, what I claim, and desire to secure by Letters Patent, is—

1. In a constant-pressure motive-fluid-operated hammer, the combination with a cylinder having an exhaust-port, of a differential piston having a through supply port or passage which is constantly open to the motive-fluid-pressure supply, and means for closing the delivery end of the through-passage before the exhaust-port of the cylinder is opened, substantially as and for the purposes specified.

2. In a constant-pressure motive-fluid-operated hammer, the combination with a cylinder having an exhaust-port, of a hollow differential piston open at the head having the lesser area and provided with a radial supply port or passage at its opposite end, substantially as and for the purposes specified.

3. In a motive-fluid-operated hammer, the combination of a cylinder and a differential piston, the piston having a supply-port therethrough and which opens on the lesser head of the piston, and the cylinder having an exhaust-port at that end of the cylinder which contains the head of the piston having the greater area, and means for maintaining a constant motive-fluid pressure in that end of the cylinder which contains the piston-head having the lesser area, substantially as and for the purposes specified.

In testimony whereof I affix my signature, in presence of two witnesses, this 3d day of June, 1901.

CHARLES HARRIS JOHNSON.
